HEEL CONSTRUCTION

Stanley Sorofman, Mattapan, Mass.

Application June 12, 1947, Serial No. 754,195

3 Claims. (Cl. 36—42)

1

The present invention relates to shoe construction and, more particularly, to the attachment of the heel to the shoe. It is common practice to attach the heel by cementing and nailing. In a method commonly followed in the art, particularly in the construction of women's shoes with high heels, the outer sole is split in the rear section, the outer portion forming a flap which is turned downward and cemented to the inner face of the heel. The other portion of the sole is cemented or tacked to the inner sole piece and thereafter trimmed around the periphery of the heel so as to fit more snugly over the base section of the sole to which the heel is commonly attached. The present invention applies equally well to half Louis, whole Louis, or any other type of heel.

Difficulty is sometimes experienced in securing the heel tightly and safely to the sole. This more often happens in the case of women's high heeled shoes, since the heel itself acts as a lever against the supporting base and may be loosened or knocked off by a comparatively light blow. In the present invention, the heel is permanently attached in such a way that it is held firmly and securely to the sole of the shoe, providing sufficient strength and durability to withstand excessive forces far above those which may ordinarily be encountered in wear and use. In the present invention, a steel shank set in the shank portion of the shoe has a rearward tongue, of spring steel if desired, extending over the heel section beneath the sole. The tongue when unrestrained may normally slope downward or away from the outer surface of the sole. The heel itself carries secured on its concave top surface a channel element which engages the tongue, providing a secure connection both against forward bending and also sideways rocking action, but permits the heel to hang slightly down from the sole. In addition to this feature, a screw, which may be of the wood screw type or a machine screw with a flat head goes through a hole in the tongue and into the top of the heel, drawing the heel up substantially flush with the bottom surface of the sole, making a firm contact between the bottom surface of the sole and the top peripheral surface of the heel. Where a machine screw is used, it may thread into the tongue and by drawing up the tongue hold the heel firmly in position.

The invention will be more fully described in the specification below when taken in connection with the drawings illustrating an embodiment of the same, in which:

2

Fig. 1 shows a side elevation with the heel not joined to the shoe;

Fig. 2 shows a side elevation of the heel attached to the shoe;

Fig. 3 shows a plan view of the top face of the heel;

Fig. 4 shows a sectional view taken on the line 4—4 of Fig. 3;

Fig. 5 shows a view similar to Figure 3 of a modification;

Fig. 6 shows a section taken on the line 6—6 of Fig. 5;

Fig. 7 shows a still further modification in the same relation as Fig. 3;

Fig. 8 shows a section on the line 8—8 of Fig. 7;

Fig. 9 shows a further modification in the same relation as the view shown in Fig. 3;

Fig. 10 shows a section on the line 10—10 of Fig. 9; and

Fig. 11 shows a view similar to Fig. 2, with a fragmentary section.

In the figures, 1 designates the heel; 2 designates the shoe in general; 3, the inner sole; and 4, the outer sole. A shank 5, made of steel or other resilient material and attached rigidly in the shank portion of the shoe as indicated, is provided with an extending steel tongue or spring or other durable material which may be bowed away from the outer surface of the inner sole, as indicated at 7. The shank and tongue may be of material other than steel, although steel is commonly used for this purpose and provides a strong and cheap construction. The steel tongue 7 before being tempered and hardened is drilled and, except in the modification of Figures 12 to 15 inclusive, is threaded near its end at 8 to receive the machine screw 9 which passes through the inner sole 3 after the heel has been slid into place.

The heel 1, as indicated in Figures 3 and 4, is provided with a plate 10, which has two attaching or fastening sections 11 and 12, which are offset from the center section 13 of the plate member. This plate member 10 is attached to the heel by means of wood screws 14 and 14, or in any other suitable manner. The plate is preferably attached to the middle of the face of the heel at the bottom or near the bottom of the concave surface 15. The heel, it should be noted, in the present construction is made concave at the top, with the periphery of the heel substantially in a plane which may be made to coincide with the plane at the lower surface of the heel section of the inner sole. When the tongue 7 is

slipped through the channel 16, the heel will be

held firmly by the tongue, since the width of the tongue is substantially the same as the width of the slot 16. However, the heel, because of the direction of the slope of the tongue, will be separated somewhat from the lower surface of the sole in the heel section. After the heel is put in place, the screw 9 is threaded into the perforation 8 in the tongue and thereby the tongue is drawn up toward the bottom surface of the sole as indicated in Fig. 11 until the edge or periphery of the heel closes tightly against the sole. This furnishes a firm attachment for the heel, and if there were any tendency previously for the heel to be slightly loose, this overcomes it and anchors the heel firmly against the heel section of the sole. The fact that the steel shank is of spring material and sloped outwardly away from the heel means that a spring tension force is always exerted on the screw 9. This tends to preserve the tight hold or union between the sole and the heel and further permits the heel to be drawn to the shoe against spring tension.

The construction of the attaching channel member may take various forms, three other modifications of which are shown in Figs. 5, 6, 7, 8, 9, and 10. In Figs. 5 and 6, the channel member 20 is formed with a C shaped section as indicated in Fig. 6, having two inwardly extending flanges 21 and 22 which lie over the tongue of the shank when the heel is in place. The channel member 20 may be fastened to the heel by means of wood screws 23, and the heel be tapped to form a threaded hole 25 into which the machine screw 9 may mesh, if desired. In this case, the hole 8 is usually tapped large enough so that the screw 9 may pass through it.

In the arrangement shown in Figs. 7 and 8, the retaining plate 26 may be held at its ends by means of wood screws 27 and 28, screwed into the heel 1. The plate 26 is provided with two pair of bent arms 29 and 30, forming a slot or channel into which the tongue passes.

In the arrangement shown in Figs. 9 and 10, the retaining member comprises two screw elements 31 and 32, formed with a wood screw threaded shank 33 and a flat looped head 34. This screw is screwed into the face of the heel with the looped head positioned in a transverse direction across the heel. Two or more such retaining screws may be used with the slots aligned parallel to one another so that the tongue may intermesh with both as the heel is put in place. In these latter modifications, the threaded screw 9 engages the end tongue 7 of the shank and pulls the latter up toward it to hold the heel firmly in place.

In the construction according to the present invention, considerable emphasis is placed upon

firmly securing the heel to the shoe. In modern shoe construction, this has proven to be a difficulty. It is essential however, particularly in the modern types of shoes which are used, to have the heel securely attached to the shoe. One reason for this is that with the present use of open heels, the heel of the foot is not always directly positioned over the heel of the shoe and as a result twists and bends and other exceptional stresses are placed upon the heel by the wearer. Further, the present tendency to make the inner sole or the sole directly beneath the heel very thin makes it difficult to fasten the heel securely to the sole. The present invention overcomes these difficulties and provides a construction which is highly useful and yet at the same time cheap as regards construction and labor costs.

Having now described my invention, I claim:

1. In a shoe construction of the type described, a heel, means forming a channel positioned at the top surface of the heel, a shank having an extension engaging said channel and retaining means extending through the sole engaging the extension beyond the position of the channel and fastening into the heel.
2. In a shoe construction of the type described, a heel, means forming a channel positioned at the top surface of the heel, a shank having a spring extension extending over the innersole in the heel and having a normal free bend away from the shoe and adapted to engage said channel and retaining means extending through the sole engaging the extension and fastening into the heel against the sole.
3. In a shoe construction of the type described, a heel, means forming a channel positioned at the top surface of the heel, a shank having a spring extension extending over the innersole in the heel and having a normal free bend away from the shoe and adapted to engage said channel, said extension beyond the channel having a threaded hole therethrough and a screw set in the inner sole and extending into said threaded hole for drawing the heel flush against the sole of the shoe.
